SAFETY DEVICE FOR COMBUSTION CHAMBERS

Aylmer H. Maude, Niagara Falls, N. Y., assignor
to Hooker Electrochemical Company, Niagara
Falls, N. Y., a corporation of New York

Application November 10, 1941, Serial No. 418,585

4 Claims. (Cl. 23—277)

My invention relates more particularly to safety devices of the character known as "frangible diaphragms," and has for its object to provide a diaphragm suitable for use in connection with hot corrosive gases and one which will be serviceable for a reasonable length of time and will afford complete protection under violent explosions.

The use of frangible diaphragms as a protection to containers filled with fluids under static pressure is known and practiced in cases where, owing to the nature of the fluid, ordinary safety valves are unreliable. However, the object of my invention is more particularly to afford protection to reactors or combustion chambers normally under slight pressure, but in which reactions are carried on which are liable to develop explosive violence. Such a reaction is that involved in the synthesis of hydrogen chloride by combustion of hydrogen with chlorine. This reaction is usually mild and easily controlled. However, mixtures of chlorine and hydrogen are highly explosive. Such mixtures are liable to form at the moment of ignition in starting up the process, or at any subsequent time if the flame should become extinguished. In such a situation, unless precautions are taken, when the gases are subsequently ignited a violent explosion is liable to occur. The gases themselves then acquire such kinetic energy that they will not turn angles, but exert their force in a straight line. To be effective therefore the frangible diaphragm must be at the end of a straight combustion chamber.

In co-pending application Serial No. 321,600, filed February 29, 1940, now Patent No. 2,295,591, of which the present application is a continuation-in-part, there is illustrated a combustion chamber of synthesis of hydrogen chloride, provided with my frangible safety diaphragm. In co-pending application Serial No. 418,586 filed of even date herewith, there is illustrated a combustion chamber of modified construction, likewise provided with my frangible safety diaphragm.

Referring to the drawing:

Fig. 1 is a sectional elevation of one form of combustion chamber embodying my invention, as illustrated in application Serial No. 418,586.

Fig. 2 is a plan view of this apparatus of Fig. 1.

Fig. 3 is an elevational view, a section, of a portion of the combustion chamber, showing the frangible diaphragm of Fig. 1 to an enlarged scale.

Fig. 4 is a sectional elevation of another form

of combustion chamber embodying my invention, as illustrated in application Serial No. 321,600.

Referring to Figs. 1, 2 and 3:

1 is a combustion chamber, cooled by water jacket 2 and provided at one end with burner 3 and at the other end with frangible diaphragm 4. 5 is the exit for hydrogen chloride, 6 an air vent and 7 an expansion joint in the water well of the jacket. Combustion chamber 1, which is preferably cylindrical, is adapted to be operated in a vertical position, and the cooling system, of which jacket 2, with water connections 8 and 9, forms a part, is designed to cool the walls to within a few degrees of the dew point of the gases, with care to avoid cooling to or below the dew point, so that the inner walls of the combustion chamber are not subjected to moist chlorine or hydrogen chloride, which of course are extremely corrosive to ordinary metals. The further details of the cooling system by which these objects are accomplished are disclosed more fully in application, Serial No. 418,586, filed November 10, 1941, and do not concern the present invention. Burner 3 is provided with inlets 10 for chlorine and 11 for hydrogen. The further details of the burner are disclosed in the application referred to and likewise do not concern the present situation.

In Figs. 1, 2 and 3 the construction of the frangible diaphragm is fully illustrated. In these figures it will be seen that diaphragm 4 is clamped between annular plate 12, which closes the upper end of water jacket 2, and annular ring 13. Diaphragm 4 therefore covers substantially the entire end of the combustion chamber opposite the burner. If an explosion should occur, its force would be principally in the direction in which the flame is directed, and since at the opposite end of the combustion chamber the entire wall is formed by the frangible diaphragm, the rupture of the diaphragm gives the maximum of relief to the combustion chamber in the minimum time.

Referring to Fig. 4: In this figure there is illustrated a modification of the apparatus of Figs. 1 to 3, in which the combustion chamber is adapted to be operated with its axis in a horizontal position. In this figure, 1A is the combustion chamber, 2A the jacket, 3A the burner, 4A the frangible diaphragms, 5A the exit for hydrogen chloride, 8A and 9A the water connections to the jacket, 10A and 11A the inlets for chlorine and hydrogen respectively, 12A the flange against which the frangible diaphragms are clamped and 13A the clamp rings.

As in the construction of Figs. 1 to 3, the walls of the combustion chamber are cooled with care to avoid going below the dew point of the gases. The details of the cooling system by which this objective is accomplished, as well as the details of the burner, are illustrated and described in parent application Serial No. 321,600, above referred to, and do not concern the present invention.

In this case the burner is let in through the top wall of the horizontal cylindrical combustion chamber, which is a side wall of the cylinder. The burner is, however, so formed that the combustion flame is directed longitudinally of the combustion chamber, as in the previous case. The burner is located near one end of the combustion chamber and the flame is directed toward the other end. This construction makes possible the use of two frangible diaphragms, one at each end of the combustion chamber.

In the construction of Fig. 4, the frangible diaphragm is of metal. However, I find that, since the diaphragm, if of metal, to be effective is necessarily very thin, and any accidental precipitation of moisture is liable to subject the diaphragm momentarily to the action of hot moist hydrogen chloride, no ordinary metal will withstand the conditions of operation very long. In fact, tantalum is about the only metal available for the purpose and this is very expensive. Hence in the construction illustrated in Figs. 1 to 3 I have sought to provide a less expensive and more permanent frangible diaphragm. I have been able to accomplish this object by providing protection for the diaphragm from the extreme heat of the combustion chamber, which enables me to make use of non-metallic, acid resistant material in its construction.

Thus, in Figs. 1 and 3 it will be seen that diaphragm 4 consists of a disc of material of the character described, clamped and forming a gasket between annular plate 12 and annular ring 13, as before stated. Beneath the diaphragm however, I provide a mat 14 of material having good heat resistant and insulating properties, such as glass wool or fibrous asbestos. This is supported by a disc 15, of heat resisting material, such as sheet asbestos, which in turn rests upon lugs 16. Mat 14 is loosely packed and of slight inertia. Disc 15 rests loosely upon lugs 16. In the event of an explosion, the entire assembly consisting of disc 15, mat 14 and diaphragm 4 is projected out of the end of combustion chamber 1. Lugs 16 are exposed to the heat of combustion, but as these are welded to a water cooled wall, they are sufficiently protected against the heat.

It will thus be seen that by the use of mat 14 as a protection for the frangible diaphragm I am able to use a diaphragm of non-metallic, acid resistant sheet material such as natural rubber or its synthetic substitutes or synthetic resins or fabric, and in particular asbestos fabric, impregnated therewith. With a combustion chamber of suitable properties and a mat of glass wool of suitable thickness, the diaphragm need never be subjected to a temperature of over 60° C. Under these conditions a diaphragm of rubberized fabric or like material lasts many months and is found to be entirely satisfactory for the purpose intended.

In place of a mat of fibrous material, obviously a light granular material, such as sand, might be employed. However, fibrous material in general provides better insulation, for a given weight, than granular material, hence is to be preferred.

as it is important to minimize the inertia of the mat.

I claim as my invention:

1. An apparatus for synthesis of hydrogen chloride by burning together gaseous hydrogen and chlorine, comprising a burner for said gases housed in an elongated, gas-tight, unlined, metal walled combustion chamber, substantially symmetrical and co-axial with respect to the burner, the end of the chamber toward which the mouth of the burner is directed being provided with a flanged opening substantially symmetrical with respect to the axis of the chamber and adequate to relieve and protect the chamber against pressures that may develop from explosive combination of the gases; a frangible diaphragm of thin, light, flexible but relatively non-heat-resistant material, resistant however to moist hydrogen chloride, clamped against the flange of said opening and making a gas-tight closure therewith; means for cooling the walls of the chamber including the surface of the flange against which the diaphragm is seated; and a layer of light, comminuted material, resistant to heat and moist hydrogen chloride and having a large proportion of voids, loosely supported between the diaphragm and burner beyond the normal reach of the burner flame, said layer being readily expellable straight outward through said opening upon explosive rupture of said diaphragm.

2. An apparatus for synthesis of hydrogen chloride by burning together gaseous hydrogen and chlorine, comprising a burner for said gases housed in an elongated, gas-tight, unlined, metal walled combustion chamber, substantially symmetrical and co-axial with respect to the burner, the end of the chamber toward which the mouth of the burner is directed being provided with a flanged opening substantially symmetrical with respect to the axis of the chamber and adequate to relieve and protect the chamber against pressures that may develop from explosive combination of the gases; a frangible diaphragm of thin, light flexible material selected from the group consisting of natural and synthetic gums and resins and textile fabrics impregnated or coated therewith, said diaphragm being clamped against the flange of said opening and making a gas-tight closure therewith; means for cooling the walls of the chamber including the surface of the flange against which the diaphragm is seated; and a layer of light, comminuted material, resistant to heat and moist hydrogen chloride and having a large proportion of voids, loosely supported between the diaphragm and burner beyond the normal reach of the burner flame, said layer being readily expellable straight outward through said opening upon explosive rupture of said diaphragm.

3. An apparatus for synthesis of hydrogen chloride by burning together gaseous hydrogen and chlorine, comprising a burner for said gases housed in an elongated, gas-tight, unlined, metal walled combustion chamber, substantially symmetrical and co-axial with respect to the burner, the end of the chamber toward which the mouth of the burner is directed being provided with a flanged opening substantially symmetrical with respect to the axis of the chamber and adequate to relieve and protect the chamber against pressures that may develop from explosive combination of the gases; a frangible diaphragm of thin, light, flexible but relatively non-heat-resistant material, resistant however to moist hydrogen chloride, clamped against the flange of said open-

ing and making a gas-tight closure therewith; means for cooling the walls of the chamber including the surface of the flange against which the diaphragm is seated; and a layer of fibrous inorganic material, resistant to heat and moist hydrogen chloride, loosely supported between the diaphragm and burner beyond the normal reach of the burner flame, said layer being readily expellable straight outward through said opening upon explosive rupture of said diaphragm.

4. An apparatus for synthesis of hydrogen chloride by burning together gaseous hydrogen and chlorine, comprising a burner for said gases housed in an elongated, gas-tight, unlined, metal walled combustion chamber, substantially symmetrical and co-axial with respect to the burner, the end of the chamber toward which the mouth of the burner is directed being provided with a flanged opening substantially symmetrical with respect to the axis of the chamber and adequate 20

to relieve and protect the chamber against pressures that may develop from explosive combustion of the gases; a frangible diaphragm of thin, light, flexible but relatively non-heat-resistant material, resistant however to moist hydrogen chloride, clamped against the flange of said opening and making a gas tight closure therewith; means for cooling the walls of the chamber including the surface of the flange against which the diaphragm is seated; a layer of fibrous inorganic material adjacent the diaphragm and a sheet of rigid material loosely supported between said fibrous layer and the burner, beyond the normal reach of the burner flame, said sheet and fibrous layer being of material resistant to heat and moist hydrogen chloride and readily expellable straight outward through said opening upon explosive rupture of said diaphragm.
